UNITED STATES PATENT OFFICE.

WILLIAM N. BRENNER, OF BROOKLYN, NEW YORK.

DEVICE FOR CONTROLLING GLARING LIGHTS OF AUTOMOBILE-LAMPS.

1,201,141.

Specification of Letters Patent. Patented Oct. 10, 1916.

Application filed January 14, 1916. Serial No. 72,153.

To all whom it may concern:

Be it known that I, WILLIAM N. BRENNER, a citizen of the United States, residing at Brooklyn, in the county of Kings and State 5 of New York, have invented certain new and useful Improvements in Devices for Controlling Glaring Lights of Automobile-Lamps; and I do hereby declare the following to be a full, clear, and exact description 10 of the invention, such as will enable others skilled in the art to which it appertains to make and use the same, reference being had to the accompanying drawings, and to the letters and figures of reference marked thereon, which form a part of this specification.

This invention relates to new and useful improvements in devices for controlling the glaring light of automobile and other lamps and consists in the provision of a folding 20 shutter adapted to regulate the space through which the light is reflected and controlled by convenient means, accessible to the operator of a car upon which the lights are mounted.

25 The invention consists of a simple and efficient apparatus of this nature having various details of construction, combinations and arrangements of parts which will be hereinafter fully described, shown in the accompanying drawings and then specifically defined in the appended claims.

My invention is illustrated in the accompanying drawings, in which:

Figure 1 is a view showing the shutters folded. Fig. 2 is a view showing the shutters thrown to reduce the space through which the light is reflected. Fig. 3 is a cross sectional view through the rim. Fig. 4 is a detail view showing the means for operating 40 the series of shutters.

Reference now being had to the details of the drawings by letter, A designates the rim of a lamp behind which the series of shutters are normally folded when not in use. Said shutters consist of strips, designated 45 respectively by letters B, which are mounted upon the pivots C, and other shutters, designated by letters D, each mounted upon the pivot C and each bearing a lug or pin E

projecting through a transverse slot F 50 formed in the adjacent shutter.

H designates recesses in the outermost of the shutters and is adapted to bear against a stop I to limit the swinging movement of the said outermost shutter. Said shutters 55 are preferably curved and, when open for use, their outer free ends are adapted to abut one another, as shown in Fig. 2 of the drawings. A crank shaft, designated by letter J, is journaled in the rim of the lamp 60 and a disk K is fastened to said crank shaft and rods M are pivotally connected eccentrically at their adjacent ends to said disk and their other ends pivoted one to each shutter B. Said crank is adapted to be connected in any manner not shown to the steering post or is positioned at any other place convenient to the operator of the vehicle upon which the lamps are mounted.

In operation, when the disk is in the position shown in Fig. 1 of the drawings, all of the various shutters will be folded back as shown, back of the rim and out of sight. When it is desired to throw the shutters to the position shown in Fig. 2, whereby the 75 space through which the light to be reflected is restricted, the shutters will assume the position illustrated and cause an opening at the lower portion of the lamp through which the concentrated rays may be thrown down 80 upon a track.

What I claim to be new is:

1. A device for controlling the glaring light upon automobile lamps, etc., comprising, in combination with a lamp, a series of 85 shutters pivotally mounted upon the rim and having sliding pivotal connection with one another, a crank shaft, a disk fitted thereto, and rods pivotally connecting said shutters and disk.

2. In combination with the rim of a lamp, a series of shutters mounted upon a common pivotal pin upon the rim, the various shutters having transverse slots, pins carried by the shutters and movable in the slots in the 95 adjacent shutters, means for limiting the movements of the shutters in one direction, a crank shaft, a disk fitted thereto, and piv-

2
otal rod connections between the same and the inner shutters.

3. In combination with the rim of a lamp, a series of shutters mounted upon a common pivotal pin upon the rim, the various shutters having transverse slots, pins carried by the shutters and movable in the slots in the adjacent shutters, stops upon the rim, pins upon the outermost shutters adapted to en-

gage said stops, a crank shaft, a disk fitted 10 thereto, and pivotal rod connections between the same and the inner shutters.

In testimony whereof I hereunto affix my signature in presence of two witnesses.

WILLIAM N. BRENNER.

Witnesses:

KATHRYN BRENNER,
CHARLES A. MARTIN.
